UNITED STATES PATENT OFFICE

HARVEY F. MORRIS, OF ROCHESTER, NEW YORK

DESIGN FOR AN EMBLEM BADGE OR SIMILAR ARTICLE

Application filed December 22, 1928. Serial No. 29,386. Term of patent 14 years.

To all whom it may concern:

Be it known that I, HARVEY F. MORRIS, a citizen of the United States, residing at Rochester, in the county of Monroe and State of New York, have invented a new, original, and ornamental Design for an Emblem Badge or Similar Article, of which the following is a specification, reference being had to the accompanying drawing, forming part thereof.

The figure is a front view of an emblem badge or similar article showing my new design.

I claim:

The ornamental design for an emblem badge or similar article, as shown.

HARVEY F. MORRIS.
